COMBINED RULE, PROTRACTOR AND ERASING SHIELD

Charles R. Meldrum, Detroit, Mich., assignor of fractional part interest to Robert G. Mentag, Detroit, Mich.

Filed Sept. 25, 1970, Ser. No. 25,196

Term of patent 14 years

Int. Cl. D10—04

U.S. Cl. D52—6

FIG. 1 is a top plan view of the combined rule, protractor, and erasing shield showing my new design; and FIG. 2 is an enlarged fragmentary section view of FIG. 1 as taken from lines 2—2.

The bottom plan of the claimed design is plain and unornamented except for the apertures shown by FIG. 1.

I claim:

The ornamental design for a combined rule, protractor and erasing shield, substantially as shown and described.
